UNITED STATES PATENT OFFICE.

LEWIS W. MILLER, OF FORT SMITH, ARKANSAS.

COMBINATION-TABLE.

No. 919,052.

Specification of Letters Patent. Patented April 20, 1909.

Application filed April 20, 1908. Serial No. 426,114.

To all whom it may concern:

Be it known that I, LEWIS W. MILLER, a citizen of the United States, residing at Fort Smith, in the county of Sebastian and State 5 of Arkansas, have invented certain new and useful Improvements in Combination - Tables; and I do declare the following to be a full, clear, and exact description of the invention, such as will enable others skilled in the 10 art to which it appertains to make and use the same.

This invention relates to combination furniture and has for its object to provide in a single piece of furniture, a table, a chest and 15 a number of folding leaves adapted to various purposes.

Another object is to provide in a combination table and chest, a novel form of chest lid which may serve also for a writing desk or 20 the like.

Another object of the invention is to provide a table which may be easily constructed without the use of special tools and which will be durable and efficient in operation.

25 For these and still other objects which will appear as the description proceeds, the invention consists of certain novel features, arrangements and combinations of parts of which the herein described table is one of 30 many possible embodiments.

In the annexed drawing forming a part of this specification like reference characters refer to like parts throughout the several views which are for illustrative purposes 35 only and therefore not drawn to any particular scale.

Figure 1 is a perspective view of one form 40 of the invention; Fig. 2 is a perspective view showing this form knocked down ready for shipping or crating; Fig. 3 is a perspective view of another form of the invention; Fig. 4 is a longitudinal vertical sectional view of the form shown in Fig. 3 certain of the movable parts being in open position and others in 45 closed position; Fig. 5 is a transverse vertical sectional view of the same.

Referring more particularly to the drawings, my invention is shown comprising a pair of front legs or supports 1, a pair of rear 50 legs 2, end chest boards 3 secured to the inner face of said legs, front and rear chest boards 4 and 5, and the top 6. The lower edge of the inner faces of the end boards 3 and the front and rear boards 4 and 5, are grooved as at 7 55 for the reception of a bottom board 8. The front and rear boards 4 and 5 are secured to

the legs 1 and 2 by screws 8 inserted from the outside and the boards 3 are secured in any convenient manner to said legs as by screws extending from the inside of said end boards. 60 The legs 4 may be provided with rollers 9.

The top 6 is provided with bracing boards or cleats 10 to which the upper end of the legs is secured. These cleats may be provided with inner guides or trackways 11 65 which may serve to support a drawer 12 as shown in Fig. 1. The trackway 11 and drawer 12 may be omitted if desired and only end cleats 10 and side cleats 13 used.

A lid member 14 is provided for the chest 70 formed by the ends 3 and sides 4 and 5. For a purpose which will appear hereinafter, the lid member is provided with links 15 pivoted to the rear end of cleats 16 formed at the ends of and serving to strengthen the lid 14 75 which may be of one continuous piece if desired. The other end 17 of the links 15 is pivoted to the inner face of the ends 3 in such a manner that when the lid 14 is at its lowest position, the cleats 16 will lie snugly within 80 the chest and so that when the lid 14 is at its uppermost position, said lid will be a considerable height above the chest and a convenient distance below the cleats 10.

Rollers 18 are secured to the inner face 85 of the legs 1 in convenient position for the cleats 16 to roll thereon when said lid is being pulled out to the position shown in Figs. 1 and 3. The cleats 16 are provided with notches 19 adapted to receive the rollers 18 90 whereby the lid 14 may be yieldably held against movement on said rollers.

The chest and lid may be provided with a suitable lock or fastening as at 20 and 21 95 if desired. The form of the invention shown in Fig. 3 is adapted to be provided with additional parts as ironing boards 23 and 24 and a leaf 25 as shown. The ironing boards are hinged beneath the ends of the table as at 26 and are provided with 100 strengthening cleats 27 secured to the larger end thereof by means of turning groove connection as shown in Fig. 4. In order to permit the boards 23 and 24 to be placed in either horizontal or folded position, is provided a folding brace 28 comprising an upper section 29 and a lower section 30 pivotally connected to each other at 31, the upper section being pivoted to a bracket 32 attached to the ironing board, the lower section being pivoted to the bracket 33 secured to the cross piece 34 passing through the 110

legs 1 and 2. A lug or the like 35 holds the brace 28 against folding outwardly but permits the same to be folded upwardly to lie substantially against the ironing board 5 when the same is in vertical position as clearly shown in Fig. 4. The leaf 25 may be provided with strengthening cleats 36 to the inner ends of which are secured hinged plates 37 pivotally secured to similar plates 10 38 screwed or otherwise fastened to the legs 2. At an intermediate point of the cleats 3 is pivotally secured one end of a brace 39 the other end of said brace being provided with teeth 40 adapted to engage 15 a screw 41 whereby said leaf 25 may be held in horizontal position, or may be adjusted to a slanting position to form a writing desk or device. The outer edge of said leaf 25 may be provided with a scale or 20 yard measure 42.

The operation of my device will be readily understood without a more extended explanation.

It will be readily seen that the lid 14 is 25 arranged not only to serve as a closure for the chest and as a table or desk but is formed of such novel construction that it forms a very convenient and efficient device for permitting easy access to the chest.

30 An article of furniture constructed in accordance with the above description requires no special material or machinery to manufacture it and at the same time furnishes a number of useful household articles 35 of furniture, combined with very small cost and occupying very small space when closed, which may at a moment's notice and with almost no trouble be extended to serve a variety of uses.

40 It is especially understood that the com-

bination table may be manufactured in a variety of styles, namely, a table without the ironing board and drop leaf, a table with drop leaf and drawer and no ironing board, a table with ironing boards attached, and with 45 ironing boards and drop leaf all attached. Particular attention is called to the convenient manner in which the table may be knocked down and crated.

When the lid 14 is drawn up in the position shown in Fig. 1, it forms an excellent writing desk or serving table and may be used to play games and as it extends over the lap is very convenient for many uses. The drop leaf can be lifted to different positions making a handy desk also. 50 55

Having thus described my invention, what I claim as new and desire to secure by U. S. Letters-Patent is:—

A device of the character described comprising a chest having legs secured thereto and projecting upwardly therefrom, a board supported upon the upper ends of said legs, a lid for said chest, said lid being provided with cleats on the lower face near opposite 65 edges thereof, links pivoted at one end to one end of said cleats, the opposite ends of said links being pivoted within said chest, said cleats being provided with notches on the lower edge near said ends thereof, and rollers 70 on two opposite legs adapted to be engaged by said notches.

In testimony whereof I have hereunto set my hand in presence of two subscribing witnesses.

LEWIS W. MILLER.
